(57) **CLAIM**

The ornamental design for an elastic membrane for semiconductor wafer polishing apparatus, as shown and described.

DESCRIPTION

FIG. 1 is a bottom plan view of a first elastic membrane for semiconductor wafer polishing apparatus showing our new design;

FIG. 2 is a top plan view thereof;

FIG. 3 is a front elevation view thereof;

FIG. 4 is an enlarged perspective view of a portion taken along section 4 in FIG. 2;

FIG. 5 is a cross-sectional view taken along the line 5-5 in FIG. 2; and,

FIG. 6 is an enlarged portion view taken along line 6-6 in FIG. 5.

The broken lines shown in the drawings represent portions of the elastic membrane for semiconductor wafer polishing apparatus that form no part of the claimed design. The dashed-dot-dashed lines represent boundary lines of the claimed design.

All surfaces not shown form no part of the claimed design.
